DESIGN FOR A GLASS HOLDER OR SIMILAR
ARTICLE

Eugene Dannemann, New York, N. Y.

Application April 22, 1946, Serial No. 128,823

Term of patent 3½ years

(Cl. D44—10)

To all whom it may concern:

Be it known that I, Eugene Dannemann, a citizen of United States, residing at New York city, in the county of Kings and State of New York, have invented a new, original, and ornamental Design for a Glass Holder or Similar Article, of which the following is a specification, reference being had to the accompanying drawing, forming part thereof.

In the drawing:

Fig. 1 is a perspective view of a glass holder showing my new design;

Fig. 2 is a top plan view thereof; and

Fig. 3 is an end edge view thereof.

Fig. 4 is a partial cross-sectional view taken on line 4—4 of Fig. 2.

I claim:

The ornamental design for a glass holder or similar article, as shown.

EUGENE DANNEMANN.
